SLUB CATCHER

Henry Owens, Edgewood, R. I., assignor to Henry
 Owens & Company, Inc., Providence, R. I., a
 corporation of Rhode Island

Application December 14, 1939, Serial No. 309,213

15 Claims. (Cl. 28—64)

My invention relates to improvements in slub catchers for use in twisting, winding, spinning, doubling, or like machines.

An object of my invention is to provide a slub catcher which may be used with a plurality of strands which may have slubs therein for twisting or doubling said strands. While I am aware that others have provided slub catchers for single strands for use in front of spinning, winding and other textile machines, so far as I am aware I am the first to provide a slub catcher actuated by a plurality of strands which on contact with a slub in any of said strands will function to break all of said strands. This feature of my invention is particularly adapted for use in twisting or doubling textile strands. Under the present standard practice, the strands come off the spinning machines in small packages and they are then wound into larger packages prior to being twisted or doubled in a twisting or doubling machine. At present various types of prior art slub catchers are employed on the winding machines. It is now possible, however, to spin into larger packages and by employing a type of slub catcher which will function on a plurality of strands constructed in accordance with my invention, I am enabled to eliminate entirely the intermediate step of winding with consequent great saving in the cost of twisted or doubled yarn.

A further feature of my invention relates to the provision of a slub catcher, whether for use with a single strand, or a plurality of strands which may be readily threaded and for this purpose I mount the operating parts, namely, the trapping or cutting means and guide or feeler members below a post or other stationary part, with the guide members substantially in rear of a downwardly tapered outer end of such a post. With this construction, it is merely necessary to lay a strand in an open guide slot on a guide member and thread it into the draft or twisting means when the strand will automatically slide into cutting or trapping position below the post.

A further feature of my invention relates to the provision of a slub catcher for use with a single strand or a plurality of strands, which is simple in design, being constructed of a small number of rugged parts, positive in their action and in which the operating parts are normally concealed within a frame, thereby substantially lessening the liability of objectionable lint, oil, etc., so often present in textile mills, clogging the operation of the slub catcher, or injuring the strands produced.

These and such other objects of my invention

as may hereinafter appear may be best understood from a description of the accompanying drawing which illustrates various embodiments thereof.

5 In the drawing, Fig. 1 is a front elevation of a slub catcher constructed in accordance with my invention for use with a plurality of strands.

Fig. 2 is a rear elevation of the slub catcher shown in Fig. 1.

10 Fig. 3 is a longitudinal sectional view taken through my device and adjacent draft roll portions with the slub catcher in open operative position.

Fig. 4 is a longitudinal sectional view taken 15 through my device after it has functioned to break all the strands on abutment of a slub in one of the strands against the guide means thereof.

Fig. 5 is a rear elevation of an alternative form 20 of my invention constructed for use with a single strand.

Fig. 6 is a longitudinal sectional view similar 25 to Fig. 4 through the embodiment of my invention shown in Fig. 5 and adjacent draft roll portions after the device has functioned to break the strand on abutment of a slub in the strand guide means thereof.

In the drawing, wherein like characters of 30 reference indicate like parts throughout, 10 and 10' generally indicate a slub catcher constructed in accordance with my invention. The preferred embodiment of slub catcher 10 shown in Figs. 1-4 is adapted for use in twisting, winding, spinning, or doubling a plurality of strands 12^a and 12^b 35 which may have slubs 14 therein. In this embodiment of my invention, I provide cutting means 16 for all said strands, preferably of unitary construction as shown in Figs. 1 and 2 and strand guide means 18 for said strands, also 40 preferably of unitary constructions and having separate strand apertures 20^a and 20^b for each respective strand, each of a size to normally permit passage of said strands 12^a and 12^b therethrough with said strand guide means 18 being movable on contact with a slub 14 in one of said strands to actuate said strand cutting means 16 to break all said strands 12^a and 12^b.

I have shown in Figs. 5 and 6 a slub catcher 10' constructed to function on a single strand 12' only having substantially the same parts. I preferably employ a post 22 or 22' mounted to extend transversely horizontally above the respective strands 12^a and 12^b or strand 12' and pivotally mounted trapping or cutting means 16 or 16' terminating in a trapping or cutting edge 24 or

24' below said post 22 or 22' adjacent the strands 12^a or 12^b or strand 12' limited in its forward pivotal trapping or cutting movement by said post 22 or 22' and I employ strand guide means 18 or 18' having a plurality of strand receiving slots 20^a and 20^b or a single slot 20' in rear of said post, so arranged and constructed that on abutment of a slab 14 or 14' in said strand 12^a or 12^b or 12' thereagainst, said strand guide means 18 or 18' may be forced by the respective strand pulling its respective slab to raise said trapping or cutting arm 16 or 16' to cause the edge 24 or 24' thereof to abut said post 22 or 22' to break both the strands 12^a or 12^b, or the single strand 12'.

It is thus apparent that both the trapping or cutting means and the strand guide means are mounted for movement below the post 22 or 22' in a position out of the way of the operation of the draft or twisting means of the machine on which the slab catcher is mounted and to permit the ready insertion of a strand or strands therein. To hasten this threading movement the outer end of the post 22 or 22' is preferably downwardly tapered as at 26 or 26' and the respective guide slots 20^a and 20^b or 20' are located in rear of the downwardly tapered outer end 26 or 26' of said transverse post 22 or 22'. To thread the slab catcher, therefore, it is apparent that it is merely necessary to place the respective strands 12^a or 12^b or the strand 12' in their respective guide slots 20^a and 20^b or 20' and thread the ends thereof in the twisting or draft means such as illustrated by the draft rolls 28 or 28' when, on rotation of the rolls in the actual textile operation, the respective strands will be pulled taut and slide off the respective downwardly tapered outer end 26 or 26' of the respective post 22 or 22' to assume a position underneath their respective post in line with their respective slots 20^a or 20^b or 20' between the respective cutting edge 24 or 24' and the respective posts 22 or 22'. It is thus obvious that the forward pivotal trapping movement of the pivotally mounted cutting or trapping means 16 or 16' is limited by its respective post.

In order that the operating parts of my device may be further concealed and removed from the objectionable lint, I preferably mount the post 22 or 22' on a frame 30 or 30' preferably of inverted U-shape mounted transversely of said machine in rear of said draft or twisting means 28 or 28'. The raised U-base 32 or 32' thereof is provided with a central transverse slot 34 or 34' over which said strands 12^a and 12^b or 12' are adapted to pass and each U-leg 31 or 31' thereof is provided with a projection 33 or 33' projecting outwardly therefrom for securement thereof to the textile machine by means of screws, or otherwise. With this construction, it is obvious that the rear pivotal movement of the trapping or cutting means 16 or 16' is limited by the rear edge of the transverse slot 34 or 34'.

I have shown in the drawing two types of connections between the guide means 18 or 18' and the trapping or cutting means 16 or 16', in the embodiment shown in Figs. 1-4 a lost motion connection between the respective guide means 18 and the cutting or trapping means 16 thereof and in my embodiment shown in Figs. 5 and 6 an integral connection between said respective guide means 18' and cutting or trapping means 16'. In both embodiments the post 22 or 22' is mounted on an extension 36 or 36' projecting upwardly from said U-shaped frame.

In both embodiments a pivot pin 38 or 38' is mounted transversely of said frame below the post 22 or 22' and the trapping or cutting means in both embodiments comprises a trapping or cutting arm 16 or 16' pivotally mounted on said pivot pin 38 or 38' extending upwardly through the respective frame transverse slot 34 or 34' and terminating in the trapping or cutting edge 24 or 24' below said post 22 or 22' adjacent the respective strand or strands 12^a and 12^b or 12' limited in its rear pivotal movement by the rear edge of the transverse slot 34 or 34' and in its forward pivotal cutting or trapping movement by said post 22 or 22'. Suitable pivot ears or 40 or 40' are provided on said upwardly extending trapping or cutting arms 16 or 16' for pivotal mounting thereof on said pivot pin 38 or 38'. In the embodiment shown in Figs. 1-4 I mount a second pivot pin 42 transversely of said frame 30 in rear of said first pivot pin 38 and I pivotally mount the guide lever 44 on said second pivot pin 42 in rear of said trapping or cutting arm 16 having a work arm 46 projecting upwardly and forwardly therefrom to abut said trapping arm 16 to advance it and a power arm 18 having the strand receiving guides 20^a and 20^b in rear of the downwardly tapered outer end 26 of said post 22 adapted on abutment of a slab 14 in said strand 12 thereagainst to move its integral respective work arm 46 to abut said trapping or cutting lever arm 16 to raise it against said post 22 to break all said strands. The lever 44 is provided with suitable ears 45 for mounting on said pivot pin 42. In the embodiment of my invention shown in Figs. 5 and 6, however, the second pivot pin 42 is omitted. The work arm 46 is omitted and the guide means 18' is integrally connected to the cutting arm 16' by the connecting portion 50' and it is apparent that employing this construction, abutment of a slab 14' against the guide means 18' will cause a positive raising of the trapping arm 16' to cause the cutting or trapping edge 24' thereof to abut the post 22' to cut all the strands 12^a and 12^b where a plurality are employed or a single strand 12' if one strand only is employed.

It is obvious, however, that the construction shown in Figs. 1-4 with a lost motion connection for a plurality of strands may be employed in the construction shown in Figs. 5 and 6 for a single strand and it is also apparent that the integral connection shown in Figs. 5 and 6 for a single strand may be equally well employed for a plurality of strands. In the embodiment of my invention shown in Figs. 5 and 6, the guide means includes a plurality of thin blades 52^a and 52^b mounted on the lever 44' so as to provide the respective slot 20' between them. This construction may, if desired, be similarly employed for a plurality of strands. The individual blades 52^a and 52^b are preferably provided with upper ends downwardly tapering from the outer to the inner edges thereof to aid in guiding the respective strand 12' into its slot 20'. The rear portion 33 or 33' of the invented U-base 32 or 32' of said frame is preferably raised upwardly, as shown, to a position adjacent the strand passing thereover to lay the respective fuzzy yarn projecting from the strand to prevent it from abutting its respective trapping arm 16 or 16' and moving it to falsely activate the slab catcher.

It is apparent that I have provided a novel

type of slab catcher which may be used for a single strand or a plurality of strands, constructed of a small number of simple parts, positive in their action, which may be readily threaded and which is particularly adapted for use in twisting or doubling strands, eliminating the former step of winding and with the other advantages mentioned above.

I employ the word "post" in the claims to include any type of a rigidly mounted member against which the cutting or trapping means may function to break the strand or plurality of strands.

It is understood that my invention is not limited to the specific embodiments shown and that various deviations may be made therefrom without departing from the spirit and scope of the appended claims.

What I claim is:

1. A slab catcher for use in twisting, doubling or like machines having twisting or draft means acting on a plurality of strands, comprising a post adapted to be mounted to extend transversely horizontally above said strands, having a downwardly tapered outer end, pivotally mounted trapping or cutting means terminating in a trapping or cutting edge below said post adjacent the strands normally biased by gravity away from said post and limited in its forward pivotable trapping or cutting movement by said post and strand guide means having a plurality of strand receiving slots in rear of the downwardly tapered outer end of said post, adapted on abutment of a slab in a strand thereagainst to raise said trapping or cutting edge against said post to break all said strands.

2. A slab catcher for use in twisting, doubling or like machines having twisting or draft means acting on a plurality of strands, comprising a post adapted to be mounted to extend transversely horizontally above said strands, a pivotally mounted trapping or cutting plate terminating in a trapping or cutting edge below said post adjacent the strands normally biased by gravity away from said post and limited in its forward pivotable trapping or cutting movement by said post and an integral strand guide means having a plurality of strand receiving slots therein in rear of said post, adapted on abutment of a slab in a strand thereagainst to raise said trapping or cutting edge against said post to break all said strands.

3. A slab catcher for use in twisting, doubling or like machines having twisting or draft means acting on a plurality of strands comprising an inverted U-shaped frame adapted to be mounted on said machine transversely in rear of said twisting or draft means having a central transverse slot therein over which said strands are adapted to pass and a post mounted to extend transversely horizontally above said strands having a downwardly tapered outer end, pivotally mounted trapping or cutting means terminating in a trapping or cutting edge below said post adjacent the strands normally biased by gravity away from said post and limited in its rear pivotable movement by the rear edge of said transverse slot and in its forward pivotable trapping or cutting movement by said post and strand guide means having a plurality of strand receiving slots in rear of the downwardly tapered outer end of said post, adapted on abutment of a slab in a strand thereagainst to raise said trapping or cutting edge against said post to break all said strands.

4. A slab catcher for use in twisting, doubling or like machines having twisting or draft means acting on a plurality of strands, comprising an inverted U-shaped frame adapted to be mounted on said machine transversely in rear of said twisting or draft means having a central transverse slot therein over which said strands are adapted to pass and a post mounted to extend transversely horizontally above said strands, pivotally mounted trapping or cutting means terminating in a trapping or cutting edge below said post adjacent the strands normally biased by gravity away from said post and limited in its rear pivotable movement by the rear edge of said transverse slot and in its forward pivotable trapping or cutting movement by said post and strand guide means having a plurality of strand receiving slots in rear of said post, adapted on abutment of a slab in a strand thereagainst to raise said trapping or cutting edge against said post to break all said strands.

5. A slab catcher for use in twisting, winding, spinning, doubling or like machines having twisting or draft means acting on a strand, comprising a post adapted to be mounted to extend transversely horizontally above said strand, having a downwardly tapered outer end, pivotally mounted trapping or cutting means terminating in a trapping or cutting edge below said post adjacent the strand normally biased by gravity away from said post and limited in its forward pivotable trapping or cutting movement by said post and strand guide means having a strand receiving slot in rear of the downwardly tapered outer end of said post, adapted on abutment of a slab in said strand thereagainst to raise said trapping or cutting edge against said post to break said strand.

6. A slab catcher for use in twisting, winding, spinning, doubling or like machines having twisting or draft means acting on a strand, comprising an inverted U-shaped frame adapted to be mounted on said machine transversely in rear of said twisting or draft means having a central transverse slot therein over which said strand is adapted to pass and a post mounted to extend transversely horizontally above said strand having a downwardly tapered outer end, pivotally mounted trapping or cutting means terminating in a trapping or cutting edge below said post adjacent the strand normally biased by gravity away from said post and limited in its rear pivotable movement by the rear edge of said transverse slot and in its forward pivotable trapping or cutting movement by said post and strand guide means having a strand receiving slot in rear of the downwardly tapered outer end of said post adapted on abutment of a slab in said strand thereagainst to raise said trapping or cutting edge against said post to break said strand.

7. A slab catcher for use in twisting, doubling or like machines having twisting or draft means acting on a strand, comprising an inverted U-shaped frame adapted to be mounted on said machine transversely in rear of said twisting or draft means having a central transverse slot therein over which said strand is adapted to pass and a post mounted to extend transversely horizontally above said strand, pivotally mounted trapping or cutting means terminating in a trapping or cutting edge below said post adjacent the strand normally biased by gravity away from said post and limited in its rear pivotable movement by the rear edge of said transverse slot and

in its forward pivotable trapping or cutting movement by said post, and strand guide means having a strand receiving slot in rear of said post, adapted on abutment of a slab in said strand thereagainst to raise said trapping or cutting edge against said post to break said strand.

8. A slab catcher for use in twisting, winding, spinning, doubling or like machines having twisting or draft means acting on a strand, comprising an inverted U-shaped frame adapted to be mounted on said machine transversely in rear of said twisting or draft means having a central transverse slot therein over which said strand is adapted to pass and a post mounted on one side thereof to extend transversely horizontally over said slot above said strand having a downwardly tapered outer end, a pivot pin mounted transversely of said frame below said post, a trapping or cutting arm pivotally mounted on said pivot pin extending upwardly through said frame transverse slot and terminating in a trapping or cutting edge below said post adjacent the strand, limited in its rear pivotable movement by the rear edge of said transverse slot, and in its forward pivotable trapping or cutting movement by said post, a second pivot pin mounted transversely of said frame in rear of said first pivot pin, a guide lever pivotally mounted on said second pivot pin in rear of said trapping or cutting arm having a work arm projecting upwardly and forwardly therefrom to abut said trapping or cutting arm to advance it and a power arm having a strand receiving guide in rear of the downwardly tapered outer end of said post adapted on abutment of a slab in said strand thereagainst to move said work arm to abut said trapping or cutting arm to raise it against said post to break said strand.

9. A slab catcher for use in twisting, winding, spinning, doubling or like machines having twisting or draft means acting on a strand comprising an inverted U-shaped frame adapted to be mounted on said machine transversely in rear of said twisting or draft means having a central transverse slot therein over which said strand is adapted to pass and a post mounted on one side thereof to extend transversely horizontally over said slot above said strand having a downwardly tapered outer end, a pivot pin mounted transversely of said frame below said post, and a lever having a trapping or cutting arm pivotally mounted on said pivot pin extending upwardly through said frame transverse slot and terminating in a trapping or cutting edge below said post adjacent the strand limited in its pivotable movement by the rear edge of said transverse slot, and in its forward pivotable trapping or cutting movement by said post, and a power arm having a strand receiving guide in rear of the downwardly tapered outer end of said post adapted on abutment of a slab in said strand thereagainst to raise said trapping or cutting arm against said post to break said strand.

10. A slab catcher for use in twisting, winding, spinning, doubling or like machines having twisting or draft means acting on a strand, comprising a post adapted to be mounted to extend transversely horizontally above said strand, a pivotally mounted trapping or cutting arm terminating in an upwardly extending trapping or cutting edge below said post adjacent the strand normally biased by gravity away from said post and limited in its forward pivotable trapping or cutting movement by said post, a guide lever pivotally mounted in rear of said trapping or cutting

arm having a work arm projecting upwardly and forwardly therefrom to abut said trapping arm to advance it and a pivotally mounted power arm having a plurality of strand receiving guides in rear of said post adapted on abutment of a slab in said strand thereagainst to raise said work arm to abut said trapping or cutting arm to raise it against said post to break said strand.

11. A slab catcher for use in twisting, winding, spinning, doubling or like machines having twisting or draft means acting on a strand, comprising a post mounted on one side thereof to extend transversely horizontally over said slot above said strand, a pivot pin mounted transversely of said frame below said post, a trapping or cutting arm pivotally mounted on said pivot pin extending upwardly through said frame transverse slot and terminating in a trapping or cutting edge below said post adjacent the strand limited in its rear pivotable movement by the rear edge of said transverse slot and in its forward pivotable trapping or cutting movement by said post, a second pivot pin mounted transversely of said frame in rear of said first pivot pin, a guide lever pivotally mounted on said second pivot pin in rear of said trapping or cutting arm having a work arm projecting upwardly and forwardly therefrom to abut said trapping or cutting arm to advance it and a power arm having a strand receiving guide adapted on abutment of a slab in said strand thereagainst to move said work arm to abut said trapping or cutting arm to raise it against said post to break said strand.

12. A slab catcher for use in twisting, winding, spinning, doubling or like machines having twisting or draft means acting on a strand comprising an inverted U-shaped frame adapted to be mounted on said machine transversely in rear of said twisting or draft means having a central transverse slot therein over which said strand is adapted to pass and a post mounted on one side thereof to extend transversely horizontally over said slot above said strand, a pivot pin mounted transversely of said frame below said post, a lever having a trapping or cutting arm pivotally mounted on said pivot pin extending upwardly through said frame transverse slot and terminating in a trapping or cutting edge below said post adjacent the strand limited in its rear pivotable movement by the rear edge of said transverse slot and in its forward pivotable trapping or cutting movement by said post and a power arm having a strand receiving guide adapted on abutment of a slab in said strand thereagainst to raise said trapping or cutting arm against said post to break said strand.

13. In a slab catcher for use in twisting or doubling a plurality of strands which may have slubs therein, cutting means for all said strands, and strand guide means having a plurality of strand apertures of a size to normally permit passage of single strands therethrough, all of the elements of one of said means being connected together to function substantially simultaneously whereby a slab in any strand contacting the side walls of its respective strand aperture may actuate said strand cutting means to break all of said strands.

14. In a slab catcher for use in twisting or doubling a plurality of strands which may have slubs therein, cutting means for all said strands, and strand guide means having a plurality of strand apertures of a size to normally permit passage of single strands therethrough, all of the ele-

ments of said strand guide means being connected together to function substantially simultaneously whereby a slab in any strand contacting the side walls of its respective strand aperture may actuate said strand cutting means to break all said strands.

15. In a slab catcher for use in twisting or doubling a plurality of strands which may have slabs therein, cutting means for all said strands, and strand guide means having a plurality of strand

apertures of a size to normally permit passage of single strands therethrough, all of the elements of said cutting means being connected together to function substantially simultaneously whereby a slab in any strand contacting the side walls of its respective strand aperture may actuate said strand cutting means to break all said strands.

HENRY OWENS.
